(57) **CLAIM**

The ornamental design for a seat module, as shown and described.

DESCRIPTION

FIG. 1 is a front, right, side perspective view of a first embodiment of the seat module of the present design;

FIG. 2 is a top plan view of the seat module of FIG. 1; FIG. 3 is a front elevational view of the seat module of FIG. 1;

FIG. 4 is a rear, left side perspective view of the seat module of FIG. 1;

FIG. 5 is a rear, right side perspective view of the seat module of FIG. 1;

FIG. 6 is a left side elevational view of the seat module of FIG. 1, the right side elevational view being a mirror image thereof;

FIG. 7 is a front, right side perspective view of a second embodiment of the seat module of the present design;

FIG. 8 is a top plan view of the seat module of FIG. 7; FIG. 9 is a front elevational view of the seat module of FIG. 7;

FIG. 10 is a rear, left side perspective view of the seat module of FIG. 7;

FIG. 11 is a rear, right side perspective view of the seat module of FIG. 7; and,

FIG. 12 is a front, right side perspective view of the seat module of FIG. 1, illustrating an alternative configuration for the seat module.
